HIGH-PRESSURE DIFFUSER

Peter A. Argentieri, Tuckahoe, N. Y., assignor to
 Connor Engineering Corporation, New York,
 N. Y., a corporation of New York

Application September 22, 1950, Serial No. 186,154

6 Claims. (Cl. 137—614.11)

1

This invention relates to improvements in an air outlet device or diffuser for air conditioning systems, an example of such device being found in co-pending application Serial No. 123,927, filed October 27th, 1949, now Patent No. 2,644,389, July 7, 1953.

As pointed out in said application, it is desirable to provide, in devices of this character, and particularly when the air ducts employed are of relatively small diameter, means by which noise conditions are materially reduced and to an extent where the noise is relatively negligible.

It is therefore the primary object of the present invention to provide an improved air outlet device of the character mentioned which is constructed and arranged in such a manner as to minimize the generation of objectionable noises upon the discharge of air therethrough. A further object of the invention is the provision of an outlet device of the above-mentioned character having an inexpensive and readily-adjustable throttling means operating to prevent the formation of high-velocity jets of large mass within the device and consequently minimizing vortex and impingement noises.

It is another object of the device to provide an outlet device of two stages, into the first of which the air will flow in an axial direction, passing through the stage in a circumferential manner, and passing through said stage will have its velocity raised and lowered with a resultant loss in static pressure and reduction in noise. After passing through this first stage, the air continues on through a second stage, also moving therethrough in a circumferential manner, the velocity being again increased and decreased with a resultant loss in static pressure. In the novel construction to be described, throttling means is provided, the adjustment thereof for both stages being performed simultaneously by rotative movement of a single shaft.

With the objects above set forth, in view, I have devised the arrangement of parts hereinafter set forth and more particularly pointed out in the claims appended hereto.

In the accompanying drawings, wherein an illustrative embodiment of the invention is disclosed, Fig. 1 is a vertical sectional view through an air outlet device embodying the features of the invention.

Fig. 2 is a sectional view, taken on the line 2—2 of Fig. 1, looking in the direction of the arrows.

Fig. 3 is a sectional view, taken on the line 3—3 of Fig. 1, looking in the direction of the arrows.

Fig. 4 is a diagrammatic view showing the in-

2

stallation of the outlet and portion of the air duct in a building.

Fig. 5 is a view, partly in section, of the outlet, with a diffuser attached, and Fig. 6 is a view looking at the underside of the structure of Fig. 5 but with the diffuser removed.

An efficient air outlet device should be provided with throttling or controlling means for the air volume, and the present invention, and in the first stage through which the air passes, operates to prevent the formation of high velocity jets of large mass within the outlet device by having the air flow from the inlet duct opening into a plenum defined by a perforated cylinder within which a closure disc or diaphragm is axially adjustable for variable throttling effects. Secured to the disc or diaphragm and thus adjustable therewith is an inner perforated sleeve located concentrically to the perforated cylinder and of substantially less diameter than the same. This arrangement of concentric, perforated, cylinders or sleeves provides uniformity of flow, breaks the air stream down into a multiplicity of streams having small mass, and before the merger of the streams, which takes place in a second stage, there is a rapid reduction in velocity.

Referring to the drawings, 13 indicates the connection tube defining the inlet of the device said tube 10 being connected to the air duct 3 by any conventional means. The air distributing duct 8 in the conventional installation, is generally located between the walls or in a ceiling space such as is indicated at 11 in Fig. 4. The housing or casing of the first stage of the air outlet device is indicated at 12 and the same may be secured to the air distributing duct 10 by means of a ring 13 to which it may be attached by screws, bolts or other equivalent fastening elements. The housing or casing 12 in the form shown is of substantially rectangular shape, and the inner surfaces of its walls receive a layer of sound absorbing material 14 to minimize noise and vibration due to air impact.

A perforated cylinder 15 having a plurality of perforations 16, thus rendering the entire area of the cylinder foraminous, is fixedly mounted within the housing 12 and located concentrically to and in axial alignment with the air duct 10. Said cylinder 15 may be secured in position by any desired means, such as by fastening elements entering through its radial flange 17 and attaching it to the end wall 18 of the housing 12.

Mounted for adjustment within the cylinder 15 is a closure disc or diaphragm 19 which is axially slidable within the cylinder to produce

the desired throttling effect without generating high velocity solid streams and resultant erratic flow within the device. Diaphragm 19 closely, but slidably fits within the cylinder 15 and is provided on one of its faces with sound absorbing material 20 which is also located within the closed end of a sleeve 21. Carried by the disc or diaphragm 19 is the perforated sleeve or small diameter cylinder 21 provided with perforations 22 throughout its area so that it is in fact foraminous in the manner of the cylinder 15. The sleeve 21 is of less diameter than the cylinder 15 so that it is spaced from the walls of the latter cylinder thus providing an annular chamber between the sleeve and cylinder, the length of said chamber being determined by the adjusted position of the throttling disc 19.

The sleeve 21 is telescopic within the inlet opening 10 as clearly seen in Fig. 1, and the adjustment of the disc or diaphragm 19, carrying the sleeve 21, is had by rotative movement of a rod or shaft 23 provided with a screw thread 24 threadably received in the internal thread of a boss or nut 25 attached to the disc or diaphragm 19. The rod is guided by a supporting sleeve 26 supported by the housing and is maintained against axial shift by the cotter pins 27 and 28 while being readily manually rotatable by means of the knob 29 secured on its end on the outside of the housing or casing of the outlet device.

As will be noted from the arrows shown in Fig. 1, the air forced through the duct 8 will enter through inlet 10 and then the perforated sleeve 21 and pass through the holes 22 thereof and enter the annular space between said sleeve and the perforated cylinder 15 to then flow laterally out through the holes 16 to enter the interior of the housing or casing 12.

The second stage of the outlet device includes a housing extension 30 attached to and forming a substantial continuation of the housing 12. Said second stage includes a devous or sinuous air passage 31 provided in its wall with a plurality of perforations 32, so that the wall of said passage is in fact foraminous. Said foraminous wall 33 has its outer surface covered by sound absorbing material 33. The outlet for the passage 31 is indicated at 34 and the passage and said outlet is contracted or of slot-like formation as best seen in Fig. 3. Below the outlet 34 is located the forward end wall 35 of the housing extension 30, said end wall being covered on its inner face by the sound absorbing material 36 over which is mounted a perforated or foraminous plate 37.

From the foregoing, the operation of the device will be clear. As previously stated, air entering through the duct 8 will pass through inlet 10 and then pass laterally through the holes in the concentric cylinders 21 and 15 and enter the interior of the chamber defined by the housing or casing 12 as clearly indicated in Fig. 2. The air will then enter the second stage, namely, the baffle passage 31 of contracted devous or sinuous form, to pass out through the outlet opening 34.

After the dampening and baffling stages have been passed as above explained, the air may be caused to emanate from any one of various devices which might be placed at the outlet opening 34, in order to introduce the air in various ways into the occupied area. An example of one arrangement of this kind is seen in Figs. 5 and 6.

Coupled or attached to the end of the housing extension 30 is an elbow 38 lined with sound absorbing material 39 and having an outlet opening 40 in which a sleeve 41 is mounted. Fitted

on the sleeve 41 is the neck 42 of a frustoconical diffuser casing 43 which extends from its neck 42 and engages the under surface of the ceiling 44. The diffuser is preferably provided with a shoulder 45 against which the air stream will impinge so as to be slightly deflected thereby, and thus the outward flow of the current will be spaced from the ceiling, and ceiling smudge prevented.

The deflector plate is shown at 46 and is flatly conical and is adjustably attached to the diffuser casing 43 by the bolts 47 by means of which it may be raised or lowered for adjustment in the known manner. To enable the throttling disc 19 to be adjusted with an arrangement of the character just described, the adjusting rod 23 is extended by means of a flexible shaft 48 which has one end coupled at 49 to the end of the rod 23 and its other end connected at 50 to a pin 51 rotatively mounted in the center of the deflector plate 46. A knob 52 is secured on the pin 51 on the outer side of plate 46 in order to turn the pin, the flexible shaft and the rod 23 to thus adjust the throttling disc 19 and secure the required control of air flow. The flexible shaft may be guided through a spider 55 mounted on the sleeve 41.

By the arrangements herein described, an effective control of noise is attained and without materially hampering the air flow.

Having described an embodiment of the invention, it is obvious that the same is not to be restricted thereto, but is broad enough to cover all structures coming within the scope of the annexed claims.

What I claim is:

1. An air outlet device for connection to the opening of an air duct comprising, a casing having inlet and outlet openings, a sleeve slidably frictionally within said inlet opening and in said air duct, said sleeve being provided with a series of perforations over the entire air distributing area of the length of the walls of the sleeve, a cylinder within said casing surrounding the sleeve and in spaced relationship thereto, the walls of said cylinder having a series of perforations disposed over the entire area thereof, a throttling disk closing the inner end of said sleeve and fixed thereto, said throttling disk being slidably frictionally within said cylinder whereby the cross-sectional areas of said cylinder and said sleeve available for passage of air may be varied simultaneously.

2. An air outlet device for connection to the opening of an air duct comprising, a casing having inlet and outlet openings, a perforated sleeve located in the inlet opening and adjustable telescopically and axially therethrough, a perforated cylinder in the casing and disposed around the adjustable sleeve and spaced therefrom, said cylinder being of an external shape different from the internal shape of the casing whereby spacing is provided between the cylinder and the interior of the casing, the cylinder normally surrounding the sleeve and being spaced therefrom, a damper in the form of a flat disk of a diameter greater than the diameter of the sleeve fitting the interior of the cylinder, said damper being attached to one end of the sleeve, said damper being adjustable axially through the cylinder for the length of the cylinder simultaneously with axial movement of the sleeve, said simultaneous adjustment of the damper and the sleeve to which it is attached acting to simultaneously vary the cross-sectional area of the cylinder and

sleeve available for the passage of air, and means operable externally of the casing for adjusting the damper.

3. An air outlet device for connection to the opening of an air duct comprising, a casing having inlet and outlet openings, a sleeve slidable within one of said openings, said sleeve being provided with a series of perforations over the air-distributing area of the walls of the sleeve, a cylinder within said casing surrounding the sleeve and in spaced relation thereto, the walls of the cylinder being provided with a series of perforations disposed over the air-distributing area thereof, a throttling disk closing one end of said sleeve and fixed thereto, said throttling disk being slidable within said cylinder to define the air-distributing area thereof, whereby the cross-sectional area of said cylinder and said sleeve available for passage of air may be varied simultaneously.

4. An outlet device for connection to the opening of an air duct comprising, a casing having inlet and outlet openings, a sleeve slidable within one of said openings, said sleeve being provided with a series of perforations over the air-distributing area of the walls of the sleeve, a cylinder within said casing surrounding the sleeve and in spaced relation thereto, the walls of the cylinder being provided with a series of perforations disposed over the air-distributing area thereof, a throttling disk closing one end of said sleeve and fixed thereto, said throttling disk being slidable within said cylinder to define the air-distributing area thereof, whereby the cross-sectional area of said cylinder and said sleeve available for passage of air may be varied simultaneously, an expansion and silencing chamber located at the outlet of the casing for co-operating with the cylinder, sleeve and disk in reducing noise created because of throttling effect secured by adjustment of said sleeve and disk attached thereto, said chamber having a sinuous passage through which the air flow passes, said passage being lined with a sound-deadening material, which material extends into and lines the interior of the casing around the cylinder therein.

5. A device for controlling the flow of air from an air duct comprising, a casing having inlet and outlet openings, a perforated cylinder located at the inlet opening, a sound-deadening material lining the casing around the cylinder, a damper in the form of a flat disk fitting the interior of the cylinder, said damper being adjustable axially through the cylinder for the length of the cyl-

inder, said adjustment of the damper acting to vary the cross-sectional area of the cylinder available for the passage of air, an expansion and silencing chamber located at the outlet of the casing, the sound-deadening material being extended through said chamber for co-operating with the lined casing and perforated cylinder therein to reduce noise created because of the throttling effect secured by the adjustment of the damper, said chamber having a sinuous passage through which the air flow passes.

6. A device for controlling the flow of air from an air duct comprising, a casing having inlet and outlet openings, a perforated cylinder located at the inlet opening, said cylinder being surrounded by sound-deadening material lining the interior of the casing, a damper in the form of a disk fitting the interior of the cylinder, said damper being adjustable axially through the cylinder, means located exteriorly of the cylinder for adjusting the damper, said adjustment of the damper acting to vary the cross-sectional area of the cylinder available for the passage of air, an expansion and silencing chamber located at the outlet of the casing, said chamber being also lined with the sound-deadening material for co-operating with the cylinder and the lined casing in reducing noise created because of the throttling effect secured by the adjustment of the damper, said chamber having a sinuous passage through which the air flow passes, the passage being of a different cross-sectional shape from the cross-sectional shape of the cylinder.
